TELEPHONE BOOTH

Percival H. Sherron, Jamaica, N. Y.

Application March 12, 1938, Serial No. 195,487

5 Claims. (Cl. 189—2)

This invention relates to an improved telephone booth. It is the object of this invention to provide a fireproof and substantially soundproof telephone booth of attractive appearance, constructed 5 preferably of metal, and so designed that the various structural elements thereof can be easily fabricated in quantity, shipped to desired locations and very readily and easily assembled without the necessity of using skilled labor.

10 In general, the telephone booth in accordance with this invention comprises a base including a separable floor, an outer wall or shell, preferably of metal, formed in a plurality of separable sections, a removable ceiling assembly including 15 a separable roof and a detachable inner shell or lining spaced from the outer wall to provide room for sound insulating material therebetween. In accordance with this invention, all of these various units will be complete in themselves, may be 20 easily fabricated from, for example, sheet metal, and may quickly be secured together to form a finished booth of rigid construction and pleasing appearance.

25 The novel features of design and structure by means of which these objects are accomplished may best be described in conjunction with the accompanying drawings, which show a preferred embodiment of the invention and various modifications.

30 In the drawings:

Figure 1 is a vertical section through the booth in accordance with this invention showing it in assembled form.

35 Figure 2 is a detail sectional view showing in perspective the interior corner construction.

Figure 3 is a fragmentary horizontal section through the assembled booth.

Figure 4 is a perspective view of the base of the telephone booth.

40 Figure 5 is a plan view of the blanks from which the base shown in Figure 4 is fabricated.

Figure 6 is a detail view showing the corner post structure.

45 Figure 7 is a plan view of the blank from which the corner post shown in Figure 6 is formed.

Figure 8 is a fragmentary detail view showing the construction of a corner angle.

50 Figure 9 is a plan view of a part of the blank from which the corner angle shown in Figure 8 is formed.

Figure 10 is a horizontal section through a modified form of booth as assembled.

55 Figure 11 is a partial horizontal section through a further modified form of booth as partly assembled.

And Figure 12 is a perspective view showing a modified type of base construction.

For convenience the several structural elements which go to make up the telephone booth in accordance with this invention will be described 5 in the order in which they are assembled when erecting the booth.

The base assembly, best shown in Figures 1 and 4, comprises two sections 1 and 1', respectively, which are mirror images of each other, 10 formed from two strips of sheet metal blanked out to the shape indicated in Figure 5. The two sections, after being formed from the sheet metal blanks by bending the blanks at right angles along the dotted lines shown in Figure 5, are 15 generally channel-shaped in cross section and have a lower flange 3 and an upper flange 5, the latter of which is provided with a plurality of apertures 7 for use in securing the other sections 20 of the booth to the base, as hereinafter described. The upper flange 5 also has a portion bent upwardly at right angles to itself to form an upright flange 9.

The floor of the booth assembly is formed of 25 a sheet metal plate 11 which rests on the flanges 3 and is bent upon itself at 13 where it extends into the doorway to maintain the floor level. A strap 15 is also welded or otherwise secured to the underside of the floor 11 from front to rear 30 along its center line to prevent sagging. When the floor has been positioned in place on the flanges 3, the two sections of the base assembly are secured together, preferably by welding, at 17.

A heavy rubber composition floor covering 19 35 is placed upon the floor 11 and extends upwardly along the inside of the base assembly nearly to the upper flange 5. If desired, the sill beneath the doorway may be protected by a metallic plate 21 secured to the doubled floor plate at 13.

The corner assemblies, four in number, are 40 next secured to the base. Each of these corner assemblies comprises a corner post and an inner corner angle secured thereto, as shown in Figures 6 to 9. Each corner post, shown in completed 45 form in Figure 6, is formed from the blank shown in Figure 7. In its completed form the corner post comprises two panels 32 and 32' extending at right angles to each other, which panels terminate at their bottom edges in an inturned flange 50 33 provided with apertures 35 and along their lateral edges in inturned flanges 31 and 31', respectively. The panels 32 and 32' are doubled upon themselves at their top edge at 37 and then bent inwardly to form a horizontal flange 39 55

spaced slightly below the top edge of the panels and provided with apertures 41.

The corner angles, shown in Figure 8 in completed form, are formed from the blank shown 5 in Figure 9 (since the structure of these corner angles is identical at the top and bottom, respectively, only the upper portion thereof is shown in these figures). Each corner angle comprises two panels 41 and 41' extending at right 10 angles to each other and formed at their top and bottom edges into outwardly extending horizontal flanges 43 provided with apertures 45.

In the case of the corner angles used in making up the two rear corner assemblies, each of 15 the panels 41 and 41' is bent outwardly along its free lateral edge to form shoulder portions 47 and 47', and then again at right angles to form offset flanges 49 and 49' extending parallel to the face of the panels.

20 In the case, however, of the corner angles making up the two front corner assemblies, one of the panels 41, 41' is formed with a shoulder 25 47 and flange 49 as indicated, but the other of the two panels is not bent along the line 42 (Figure 9) but only along the line 40 to give a single outwardly extending flange 49''.

The corner angles are secured to the corner posts to form the completed corner assemblies with the lower flanges 43 of the corner angles 30 resting on the flange 33 of the corner post and the upper flanges 43 of the corner angles positioned immediately beneath the flange 39 of the corner post. The flanges 49 and 49' are then secured, preferably by welding, to the inner face 35 of the panels 32, 32' of the corner post in the case of the two rear corner assemblies; while in the two front corner assemblies flange 49 is secured to the inner face of the panel 32 of the corner post and the flange 49'' is secured, preferably by 40 welding, to the inner side of the flange 31' of the corner post.

In securing the corner assemblies to the base, the flanges 33 on the corner assemblies are placed upon the upper face of the flange 5 on the base 45 and the corner assembly is then secured in place by machine screws 51 which pass through the apertures 7 in the flange 5 and enter the tapped holes 35 in the flange 33 and 45 in the flanges 43.

Three side panels 61, each identical in structure, form the outer side walls of the booth. Each side panel 61 is formed at its lower edge with an inturned horizontal flange 63 and at its upper edge is doubled upon itself at 65 and then bent inwardly at right angles to form a horizontal flange 67 spaced below the upper edge of the panel 61 and provided with a plurality of apertures 68. Along each lateral edge the panel 61 is bent inwardly at right angles to form a shoulder 71 and is then bent again at right angles to form an offset flange 73 extending parallel to the face of the panel 61. The flange 73 is not quite co-extensive in height with the panel 61, being cut off at a point 69, spaced slightly below the 65 level of the flange 67. Secured to the flange 73, preferably by welding, is an angle bar 75 so positioned as to leave a relatively narrow outwardly opening slot between its free flange and the shoulder 71.

70 In erecting the side wall panels 61 they are put in position between the erected corner assemblies with the flanges 31, 31' of these assemblies positioned in the slot formed between the angle iron 75 and the shoulder 71, as shown in Figures 2 and 75 3. The bottom flange 63 rests upon the flange 5

of the base assembly and is secured thereto by bolts 72.

Next, the inner wall panels 81 are secured in position with, if desired, bats of sound insulating material 82 positioned between them and the outer wall sections 61. Each of these sheet metal inner wall panels 81 is formed at its top edge with a horizontally extending apertured flange 83, and along its side edges with inturned flanges 85, which preferably will be slightly outwardly sprung. Each panel 81 is put in position, as shown in Figures 2 and 3, with its lower edge secured inside the upright flange 9 of the base assembly and with its upper flange 83 positioned immediately beneath (or above) the flange 67 of 15 the outer wall panel. The flanges 85 extend into the space between the edge of the flanges 73 of the outer wall panels and the shoulders 47, 47' of the corner assemblies and in frictional engagement with the shoulders 47, 47'.

20 Above the doorway is a lintel section 91 comprising a sheet metal panel bent inwardly at the base and then upwardly to form a flange 93 and bent upon itself along its upper edge at 95 and then inwardly to form a horizontal flange 97. 25 The lintel section is bent inwardly along its lateral edges to form inturned flanges 99 which are secured to the flanges 31, 31' of the front corner assemblies by machine screws 101. A plate 103 secured to the flange 93 carries a guideway or 30 track 105 for a roller bearing 107 secured to the bracket 109 of the door 111 whereby the door is guided.

The door 111 may be any conventional folding leaf door, but preferably will be of the type disclosed in my co-pending application Serial No. 120,324, filed January 13, 1937. The door will be hinged to one of the panels 41, 41' of the front corner assemblies.

The ceiling assembly, as shown in Figure 1, is 40 substantially identical with that disclosed in my co-pending application Serial No. 120,322, filed January 13, 1937. It is preferably formed of a single sheet of metal bent to form a horizontal flange 121 extending about the outer edge of the 45 assembly, an upright rib 123 of double thickness and a depending portion 125 extending nearly to the top of the doorway and provide a compartment 127 in which a light ventilating means, etc., 50 may be positioned and which can communicate with the interior of the booth through ventilating openings or glass covered windows.

The ceiling assembly is secured in place at the top of the booth by machine screws 129 which pass through the flange 121 into tapped holes in 55 the flanges 39 and 43 of the corner assemblies, flanges 67 and 83 of the wall section assemblies and flange 97 of the lintel assembly.

In Figure 10 there is shown in cross-sectional view a modified type of booth construction in accordance with this invention. In this construction two side wall assemblies, which are mirror images one of the other, are connected together by a rear wall assembly. Each side wall section comprises an outer wall of sheet metal formed 65 into a side panel 135 extending the entire width and height of the booth, a front panel 135 extending to the edge of the doorway and terminating in an inturned flange 139, and a back panel 141 extending laterally the same distance 70 as the front panel and likewise ending in an inturned flange 143. The base of this sheet metal wall throughout the front, side and back panels is provided, as in the modifications previously described, with an inturned flange by 75

means of which it is secured to the base section.

Vertical columns 145 of channel cross section are positioned immediately in back of the front panels 137 with their flanges welded to the side panels 135 and the flanges 139, respectively. The column is provided at its base with an inturned flange by means of which it is secured to the base assembly. The angle between the side panels 135 and the rear panels 141 is strengthened by vertical column members 147 of W-cross section, the flanges of which are welded to the side and rear panels, respectively.

The two side assemblies are connected together at the rear of the booth by means of a rear wall assembly comprising a single sheet metal panel 149 having inturned flanges 151 along its lateral edges. As in the modifications earlier described, it is provided with a horizontal inwardly-extending flange along its lower edge so that it may be secured to the base assembly. The upper portions of the side wall and rear wall assemblies are bent upon themselves exactly as in the modification previously described and illustrated in, for example, Figure 2, to give a horizontal flange corresponding to the flange 67 shown in that figure.

In assembling the booth shown in Figure 10, the two side assemblies and the rear assembly are secured to the base, and the side and rear assemblies are then secured together by bolts 153 passing through the flanges 143 and 151.

The inner wall of the booth shown in Figure 10 is formed of three sheet metal panels 81' substantially identical in construction with the panels 81 previously described. The inturned flanges provided along the lateral edges of these panels 81' engage the strengthening columns 145 and 147 to secure the panels in place.

In Figure 11 there is shown in horizontal cross section a partial view of a further modified type of construction in accordance with this invention. In this boltless type of construction separate front panels 155 are provided which are welded to vertical channel columns 145', one lateral edge of the panel 155 being bent parallel to the face to form the flange 157 to which is welded an angle iron 159 in such manner as to leave a slot 161 slightly greater in thickness than the sheet metal used for the outer walls. Similarly, a rear panel 163, extending substantially the entire width and height of the rear wall is, along its lateral edges, bent twice at right angles to form the flanges 165 and 167 to the latter of which is welded an angle iron 169 so as to form a slot 171 similar to the slot 161. Each of the side panels 173, which extend substantially the entire width and height of the side walls, is bent along its lateral edges to form the flanges 175 and 177. In assembling the booth the flanges 177 are slipped into the slots 161 and 171 where, when the booth is finally assembled, they are securely retained.

In Figure 12 there is shown a modified type of base construction in accordance with this invention, whereas in the base construction shown in Figure 4 the base assembly was formed of two channel shaped members secured together at 17 and a one-piece metal floor 11. The modified structure shown in Figure 12 comprises a base assembly formed from a single member of channel cross section but provided with a ledge 5' and upturned flange 9' identical in structure and function with those of the base assembly shown in Figure 4. The floor, however, is, necessarily in this modified structure, formed from two sheet metal plates 11' and 11'', which are mirror images one of the other. These plates rest along

the inside wall of the base on the lower flanges of the wall section of the base and are bent over upon themselves at 13' at the bottom of the doorway and at 15' where they meet in the center of the booth so as to maintain the floor level.

This application is filed as, and constitutes, a continuation-in-part of my co-pending application Serial No. 125,394, filed February 12, 1937.

What I claim and desire to protect by Letters Patent is:

1. A telephone booth of the character described comprising a base including an inwardly extending horizontal ledge, a flange extending upwardly from the inner edge of said ledge, a plurality of outer wall sections each detachably secured at its lower edge to said ledge and along a lateral edge to an adjoining wall section, a plurality of inner wall sections detachably secured to the outer wall structure, the bottom edges of said inner wall sections being engaged and held in position by said upwardly extending flange on the base, and a removable roof closing the top of the booth.

2. A telephone booth of the character described comprising a base, a plurality of outer wall panels, a plurality of corner post elements designed to form with the said panels the outer wall of said booth, each of said corner post elements comprising a pair of spaced apart members forming outer and inner corner elements, means for detachably securing the outer wall panels to said base, means for detachably securing the said corner post elements to said base, means for detachably securing the said panels and corner post elements together, including a vertically extending, outwardly opening slot positioned adjacent the lateral edge of one of said named members and an inturned flange adapted to be positioned in said slot positioned adjacent the lateral edge of the other of said named members, a plurality of inner wall panels, means for detachably securing said inner wall panels to the outer wall structure including inturned flexible flanges extending along the lateral edges of each inner wall panel and adapted to frictionally engage the inner corner element of the corner post, whereby said inner wall panels form with said inner corner elements the inner wall or lining of said booth, and a removable roof closing the top of the booth.

3. A telephone booth of the character described comprising a base including an inwardly extending horizontal ledge, a flange extending upwardly from the inner edge of said ledge, a plurality of outer wall sections each detachably secured at its lower edge to said ledge and along a lateral edge to an adjoining wall section, and a plurality of inner wall sections detachably secured to the outer wall structure, the bottom edges of said inner wall sections being engaged and held in position by said upwardly extending flange on the base.

4. A telephone booth of the character described comprising a base, a plurality of outer wall panels, a plurality of corner post elements designed to form with the said panels the outer wall of said booth, each of said corner post elements comprising a pair of spaced apart members forming outer and inner corner elements, means for detachably securing the outer wall panels to said base, means for detachably securing the said corner post elements to said base, means for detachably securing the said panels and corner post elements together including a vertically extend-

- ing, outwardly opening slot positioned adjacent the lateral edge of one of said named members and an inturned flange adapted to be positioned in said slot positioned adjacent the lateral edge 5 of the other of said named members, a plurality of inner wall panels, and means for detachably securing said inner wall panels to the outer wall structure including inturned flexible flanges extending along the lateral edges of each inner wall 10 panel and adapted to frictionally engage the inner corner element of the corner post, whereby said inner wall panels form with said inner corner elements the inner wall or lining of said booth.
- 15 5. A telephone booth of the character described comprising a base, a plurality of outer wall panels, a plurality of corner post elements designed to form with the said panels the outer wall of

said booth, each of said corner post elements comprising a pair of spaced apart members forming outer and inner corner elements, means for detachably securing the outer wall panels to said base, means for detachably securing the said corner post elements to said base, means for detachably securing the said panels and corner post elements together, a plurality of inner wall panels, and means for detachably securing said inner wall panels to the outer wall structure including inturned flexible flanges extending along the lateral edges of each inner wall panel and adapted to frictionally engage the inner corner element of the corner post, whereby said inner wall panels form with said inner corner elements 10 the inner wall or lining of said booth. 15

PERCIVAL H. SHERRON.
